UNITED STATES PATENT OFFICE.

WILLIAM H. WIGMORE, OF PHILADELPHIA, PENNSYLVANIA.

APPARATUS FOR EXERCISING THE TYMPANUM.

SPECIFICATION forming part of Letters Patent No. 627,790, dated June 27, 1899.

Application filed February 6, 1899. Serial No. 704,621. (No model.)

To all whom it may concern:

Be it known that I, WILLIAM H. WIGMORE, a citizen of the United States, and a resident of the city and county of Philadelphia, State of Pennsylvania, have invented certain new and useful Improvements in Apparatus for Exercising the Tympanum, of which the following is a specification.

My invention relates to improvements in apparatus for exercising the tympanum or ear-drum; and it consists of an air-pump, means, preferably a water-motor, for operating said pump, a valve for controlling the pressure and suction of the pump, and a tube for connecting the pump with the ear of the patient.

In the accompanying drawings, which form part of this specification, Figure 1 is a perspective view, partly broken away, of my improved apparatus; and Fig. 2, a central sectional elevation through the air-controlling valve.

a is a water-wheel inclosed in a case *b*; *c*, the port for the entrance of water; *d*, the port for the discharge of the water; *e*, a shaft upon which wheel *a* is carried and which is carried in bearings in case *b*; *f*, a pulley or fly-wheel on shaft *e*; *g*, a handle by means of which this shaft may be turned by hand; *h*, a crank upon shaft *e*, to which is attached one end of a piston-rod *i*, which is attached to a piston *j*, working in a cylinder *k*; *l*, a flexible pipe leading from cylinder *k* to the ear of the patient and equipped with a tip *m* to be inserted in the ear; *n*, a valve between pipe *l* and the pump-cylinder *k*.

In the valve *n* is a disk *o*—say of rubber—placed loosely in the stem *p*.

r is a cap furnished with slots *s* on its sides, which is adapted to be placed over stem *p* and to be moved up and down on this stem to open or close the valve, as may be desired.

The shaft *e* being revolved, the piston *j* is reciprocated in cylinder *k*. On the downward stroke the air in the piston is driven into the ear through tube *l*. On the upward stroke the air is sucked back into the cylinder, and the ear-drum is thereby moved in and out.

By raising the cap *r* a certain amount of air, depending upon the distance that the cap is raised, compressed on the downward stroke of the piston will escape through valve *n* instead of passing to the ear; but the suction of the pump on the upstroke of the piston, the valve automatically closing on this stroke, remaining substantially the same the drum will be drawn out more than it has been pushed in. By adjusting the valve varying degrees of pressure may be given to the ear.

The shaft *e* is preferably revolved by the water-wheel; but it may be driven by a belt on fly-wheel or pulley *f*, or this wheel *f* may be rotated by means of the handle *g*.

Having thus described my invention, I claim as new and desire to secure by Letters Patent—

1. In an apparatus for exercising the tympanum, in combination, a pump operating upon one stroke to force air into and upon the other to exhaust it from the ear, a tube leading from said pump, a tip carried by said tube adapted to be inserted in the ear, and an adjustable relief-valve between the pump and the tip adapted to open to regulate the pressure of air in said tube on the compression stroke of said pump and to close upon its suction stroke.

2. In an apparatus for exercising the tympanum, in combination, a pump operating upon one stroke to force air into and upon the other to exhaust it from the ear, a tube leading from said pump, a tip carried by said tube adapted to be inserted in the ear, an adjustable relief-valve between the pump and the tip adapted to open to regulate the pressure of air in said tube upon the compression stroke of said pump and to close upon the suction stroke, a case having a water inlet and outlet, a water-wheel within said case, a crank upon the shaft of said wheel, and a rod connecting said crank and the piston of said pump.

WILLIAM H. WIGMORE.
